(57) **ABSTRACT**

An antenna device includes a main board, a ground board, a patch, a power feeder, a short-circuit portion and an additional conductor. The main board is made of a dielectric material. The ground board is disposed at the main board and supplies a ground potential. The patch is disposed at the main board to face the ground board in a thickness direction of the main board. The power feeder is disposed at the main board and electrically connected to the patch. The short-circuit portion is a via conductor disposed at the main board, and is electrically connected to the patch and the ground board. The additional conductor is disposed at the main board such that a side surface of the additional conductor faces a side surface of the patch, and has a potential identical to the ground potential of the ground board.

ANTENNA DEVICE WITH PATCH
INCLUDING A SLITCROSS REFERENCE TO RELATED
APPLICATION

This application is based on Japanese Patent Application No. 2020-142758 filed on Aug. 26, 2020, the disclosure of which is incorporated herein by reference.

TECHNICAL FIELD

The present disclosure relates to an antenna device.

BACKGROUND

An antenna device may include a zeroth-order resonant antenna having a ground board and a patch.

SUMMARY

The present disclosure describes an antenna device including a main board, a ground board, a patch, a power feeder, a short-circuit portion and an additional conductor.

BRIEF DESCRIPTION OF THE DRAWINGS

The objects, features and advantages of the present disclosure will become more apparent from the following detailed description made with reference to the accompanying drawings. In the drawings:

FIG. 1 is a plan view showing an antenna device according to a first embodiment;

FIG. 2 is a cross-sectional view taken along line II-II of FIG. 1;

FIG. 3 is a cross-sectional view taken along line III-III of FIG. 1;

FIG. 4 is a sectional view taken along line IV-IV of FIG. 1;

FIG. 5 is an equivalent circuit diagram of a reference example;

FIG. 6 is a diagram in which region VI of FIG. 1 is enlarged;

FIG. 7 is an equivalent circuit diagram of the first embodiment;

FIG. 8 illustrates the reflection characteristics;

FIG. 9 illustrates radiation characteristics of the first reference example;

FIG. 10 illustrates radiation characteristics of the second reference example;

FIG. 11 illustrates radiation characteristics of the first embodiment;

FIG. 12 illustrates a relationship between a position of a connecting portion and reflection characteristics;

FIG. 13 illustrates an arrangement of the connecting portion;

FIG. 14 is a plan view showing a modified example;

FIG. 15 is a plan view illustrating a modified example;

FIG. 16 is a plan view illustrating a modified example;

FIG. 17 is a diagram in which region XVII of FIG. 15 is enlarged;

FIG. 18 is an equivalent circuit diagram of the modified example illustrated in FIG. 15;

FIG. 19 is a plan view illustrating a modified example;

FIG. 20 is a plan view illustrating a modified example;

FIG. 21 is a plan view illustrating a modified example;

FIG. 22 is a plan view illustrating a modified example;

2

FIG. 23 is a plan view showing an antenna device according to a second embodiment;

FIG. 24 is a diagram in which region XXIV of FIG. 23 is enlarged;

FIG. 25 illustrates an equivalent circuit diagram;

FIG. 26 illustrates the reflection characteristics;

FIG. 27 illustrates the radiation characteristics;

FIG. 28 is a plan view illustrating a modified example; and

FIG. 29 is a plan view illustrating a modified example.

DETAILED DESCRIPTION

In a zeroth-order antenna, an additional conductor may be disposed at a side opposite to a ground board with respect to a patch. In this structure, a capacitor, which is formed between the patch and the additional conductor, is connected to a capacitor formed between the patch and the ground board in parallel. Therefore, a capacitance value of the capacitor in the LC parallel resonance circuit becomes larger, and the resonance frequency is shifted to a lower frequency side as compared with a structure without having the additional conductor. In order to obtain a predetermined resonance frequency at a higher frequency side, for example, it may be required to reduce the area of the patch.

The zeroth-order resonant antenna may adopt a main board made of a dielectric material. Conductors such as a ground board, a patch, and a short-circuit portion may be disposed at the main board. The short-circuit portion may include a via conductor arranged on the main board. It may be difficult to enhance the reflection characteristics as having restrictions on, for example, the thickness of the main board and the via diameter. Therefore, there is a demand for further enhancement on the antenna device.

According to an aspect of the present disclosure, an antenna device includes a main board, a ground board, a patch, a power feeder, a short-circuit portion and an additional conductor. The main board is made of a dielectric material. The ground board is disposed at the main board and supplies a ground potential. The patch is disposed at the main board to face the ground board in a thickness direction of the main board. The power feeder is disposed at the main board and electrically connected to the patch. The short-circuit portion is a via conductor disposed at the main board, and is electrically connected to the patch and the ground board. The additional conductor is disposed at the main board such that a side surface of the additional conductor faces a side surface of the patch, and has a potential identical to the ground potential of the ground board. The patch includes an outer surface, at least one slit and an inner surface. The outer surface defines an outer contour of the patch, and the outer surface is the side surface of the patch. The slit opens to a position, which is apart from a part of the outer surface electrically connected with the power feeder.

The inner surface defines the slit, and the inner surface is the side surface of the patch. The additional conductor includes a base portion, an inserting portion and a connecting portion. The base portion extends in an extending direction along the outer surface of the patch, and is disposed to face the outer surface around the aperture of the slit. The inserting portion is connected to the base portion, and is disposed inside the slit to face the inner surface of the patch. The connecting portion extends from the base portion, and electrically connects the ground board and the additional conductor.

According to the antenna device described above, a capacitor is formed at a part where the base portion of the additional conductor and the outer surface of the patch face

each other. The connecting portion of the additional conductor includes an inductor. The capacitor and inductor shift the resonance frequency to a higher frequency side. Even though the area of the patch is not reduced, it is possible to shift the resonance frequency to a higher frequency side with respect to the structure without having the additional conductor.

A capacitor is formed at a portion where the inserting portion of the additional conductor faces the inner surface of the patch. This capacitor enhances the reflection characteristics. As a result, it is possible to enhance the reflection characteristics while shifting the resonance frequency to the higher resonance frequency side without changing the physical size of the patch.

Hereinafter, multiple embodiments will be described with reference to the drawings. The same reference numerals are assigned to the corresponding elements in each embodiment, and thus, duplicate descriptions may be omitted. When a part of the features in each embodiment is explained, the remaining part of the features may be provided by the features in other prior explained embodiment. Further, not only the combinations of the configurations explicitly shown in the description of the respective embodiments, but also the configurations of the plurality of embodiments can be partially combined even when they are not explicitly shown as long as there is no difficulty in the combination in particular.

First Embodiment

An antenna device according to the present embodiment transmits and/or receives radio waves of a predetermined operating frequency. The antenna device transmits and/or receives radio waves in a frequency band used in a short-range wireless communication. The operating frequency in the present embodiment is 2.44 GHz. The operating frequency may be appropriately designed and may be another frequency (for example, 5 GHz). In the following, the opposite means a state in which two objects face each other with a predetermined distance.

Structure of Antenna Device

First, the following describes the structure of the antenna device with reference to FIGS. 1 to 4. FIG. 1 is a plan view of the antenna device according to the present embodiment in a board thickness direction of a board viewed from a patch. FIG. 2 is a cross-sectional view taken along line III-III of FIG. 1. FIG. 3 is a cross-sectional view taken along line III-III of FIG. 1. FIG. 4 is a cross-sectional view taken along line IV-IV of FIG. 1.

As illustrated in FIGS. 1 to 4, an antenna device 10 includes a main board 20, a ground board 30, a patch 40, a power feeder 50, a short-circuit portion 60. The antenna device 10 is configured on a printed circuit board. In other words, the antenna is mounted on the printed circuit board. The main board 20 is, for example, an insulating base material of a printed circuit board. The main board 20 may also be referred to as a substrate or a main plate. The elements other than the main board 20, that is, the ground board 30, the patch 40, the power feeder 50, and the short-circuit portion 60 are conductor elements of the printed circuit board. The ground board 30 may also be referred to as a ground plate or bottom plate. The patch 40 may also be referred to as a patch portion. The power feeder 50 may also be referred to as an electric feeding line, a power feeding line, or a power supply line.

In the following, a board thickness direction of the main board 20 is defined as a Z direction, and one direction orthogonal to the Z direction is defined as a X direction. The direction orthogonal to the Z direction and the X direction is defined as the Y direction. Unless otherwise specified, a shape viewed in a plane from the Z direction, that is, a shape along an XY plane defined by the X and Y directions is referred to as a planar shape.

The main board 20 is made of a dielectric material such as resin. By using the main board 20, a wavelength shortening effect by the dielectric material can be expected. As the main board 20, for example, a member made of only resin, or a combination of resin and glass cloth, non-woven fabric, or the like can be adopted. The main board 20 functions as a holding portion that holds the ground board 30 and the patch 40 in a predetermined positional relationship.

The main board 20 includes a main surface 20a and a rear surface 20b as a surface opposite to the main surface 20a in the Z direction. In the present embodiment, the ground board 30 is disposed at the main surface 20a of the main board 20, and the patch 40 and the power feeder 50 are disposed at the rear surface 20b of the main board 20. Depending on the thickness of the main board 20, an opposite distance between the ground board 30 and the patch 40 and a length of the short-circuit portion 60 in the Z direction can be adjusted. The main board 20 may have a single-layer structure or a multi-layer structure.

The ground board 30 is connected to a feeder circuit (not shown) to supply a ground potential of the antenna device 10. The ground board 30 provides a ground potential by electrically connecting, for example, an external conductor of a coaxial cable. The ground board 30 is a flat plate-shaped conductor made of copper or the like. The direction perpendicular to a board surface of the ground board 30 is also substantially parallel to the Z direction. In a plan view, the area of the ground board 30 is larger than the area of the patch 40. The ground board 30 has a size that includes the entire patch 40. The ground board 30 may have a size required for stable operation of the antenna device, in other words, zeroth-order resonant antenna.

The ground board 30 of the present embodiment has a substantially rectangular planar shape. Each side of the ground board 30 has a length of, for example, one or more times the wavelength of the radio wave of the operating frequency, that is, one wavelength or more. The ground board 30 is disposed at the main surface 20a of the main board 20 as described above. The ground board 30 is formed by patterning a metal foil arranged at the main surface 20a of the main board 20. The planar shape of the ground board 30 can be changed as appropriate. In the present embodiment, the planar shape of the ground board 30 is a rectangle as an example, but as another configuration, the planar shape of the ground board 30 may be square or other polygonal shapes. Further, the planar shape of the ground board 30 may be circular (including an ellipse). The ground board 30 may be formed to have a size larger than a circle having a diameter of one wavelength.

The patch 40 is a conductor made of copper or the like. The patch 40 is a conductor arranged to face the ground board 30 so as to have a predetermined distance from the patch 40 in the Z direction. The patch 40 may also be referred to as a radiating element. In a plan view, the entire patch 40 overlaps the ground board 30. That is, the entire board surface (lower surface) of the patch 40 faces the ground board 30 in the Z direction. The patch 40 is arranged substantially parallel to the ground board 30. Substantially parallel is not limited to perfect parallelism. For example,

the patch 40 may be tilted by several degrees to ten degrees with respect to the ground board 30.

The patch 40 according to the present embodiment is disposed at the rear surface 20b of the main board 20 as described above. The patch 40 is formed by patterning a metal foil arranged at the rear surface 20b of the main board 20. The basic shape of the patch 40 is a substantially square. The patch 40 has a substantially H-shape by providing two slits 41 described later in a substantially square shape. The basic shape is the outer contour of the patch 40 in a plan view. The patch 40 has four sides that define the outer contour in a plan view. The patch 40 includes power feeding side 40a, adjacent sides 40b, 40c, and an opposite side 40d. The power feeding side 40a is electrically connected with the power feeder 50. The adjacent sides 40b, 40c connect the power feeding side 40a. The opposite side 40d is at a position opposite to the power feeding side 40a. The power feeding side 40a and the opposite side 40d are substantially parallel in the X direction. The adjacent sides 40b, 40c are substantially parallel in the X direction.

The patch 40 and the ground board 30 are disposed to face to each other to form an electrostatic capacitor according to an area of the patch 40 and the distance between the patch 40 and the ground board 30. The patch 40 is formed to have a size that forms a capacitance or a capacitor that resonates in parallel with the inductance of the short-circuit portion 60 at a target frequency. The area of the patch 40 is appropriately designed to provide the desired capacitance and thus to operate at the operating frequency.

In the present embodiment, the basic shape, in other words, the outer contour of the patch 40 is square as an example, but as another configuration, the planar shape of the patch 40 may be circular, regular octagon, regular hexagon, or the like. The basic shape of the patch 40 may have a line-symmetrical shape, that is, a bidirectional line-symmetric shape, with each of two straight lines orthogonal to each other as axes of symmetry. The bidirectional line-symmetrical shape refers to a figure that is line-symmetric with a first straight line as an axis of symmetry, and that is also line-symmetric with respect to a second straight line that is orthogonal to the first straight line. The bidirectional line-symmetrical shape corresponds to, for example, an ellipse, a rectangle, a circle, a square, a regular hexagon, a regular octagon, a rhombus, or the like. Further, the patch 40 may also be a point-symmetrical figure such as a circle, a square, a rectangle, or a parallelogram.

The power feeder 50 is a conductor for supplying electricity to the patch 40. The power feeder 50 extends in a direction perpendicular to the Z direction from an edge portion of the patch 40. The power feeder 50 includes a portion extending from the power supply point along a virtual straight line connecting a substantially center of the patch 40 and the power supply point. One of the end portions of the power feeder 50 is electrically connected to the end portion of the patch 40. The other end portion of the power feeder 50 is electrically connected to the inner conductor of the coaxial cable. The connecting portion between the power feeder 50 and patch 40 corresponds to the power supply point. The current flowing into the power feeder 50 through the coaxial cable is conducted to the patch 40 and resonates the patch 40. The power supply method is not limited to the direct power supply method. A power supply method in which the power feeder 50 and the patch 40 are electromagnetically coupled may also be adopted.

The power feeder 50 according to the present embodiment is a conductor disposed at the rear surface 20b of the main board 20 as described above. This conductor is sometimes

referred to as a microstrip line. The power feeder 50 is formed by patterning a metal foil arranged at the rear surface 20b of the main board 20. The power feeder 50 is formed integrally with the patch 40. The power feeder 50 extends in the X direction from the power feeding side 40a of the patch 40. The power feeder 50 is connected to a substantially central portion of the power feeding side 40a in the Y direction. The power feeder 50 has a substantially L-shaped in a plan view. The power feeder 50 extends in the X direction from the edge portion of the patch 40, and extends in the Y direction from the end portion of the extending portion in the X direction. The power feeder 50 is arranged to face the ground board 30 in the Z direction.

The short-circuit portion 60 electrically connects, that is, short-circuits the ground board 30 and the patch 40. The short-circuit portion 60 is a columnar conductor arranged at the main board 20. One of the end portions of the short-circuit portion 60 is connected to the ground board 30, and the other one of the end portions of the short-circuit portion 60 is connected to the patch 40. The short-circuit portion 60 has, for example, a substantially circular plane. By adjusting the diameter and length of the short-circuit portion 60, the inductance provided in the short-circuit portion 60 can be adjusted. The short-circuit portion 60 is connected to substantially the center of the patch 40 in a plan view. Further, the center of the patch 40 corresponds to the centroid of the patch 40.

Since the patch 40 according to the present embodiment has a square planar shape, the center corresponds to an intersection of two diagonal lines of the patch 40. The short-circuit portion 60 is a via conductor in which a conductor is arranged in a through hole formed at the main board 20. The through hole may also be referred to as a via. The through hole penetrates the main board 20 from the main surface 20a to the rear surface 20b. The number of via conductors constituting the short-circuit portion 60 is not particularly limited. In the present embodiment, one via conductor includes the short-circuit portion 60. The short-circuit portion 60 may be formed by multiple via conductors arranged in parallel between the ground board 30 and the patch 40.

The antenna device 10 further includes a shield portion 70. The shield portion 70 has the same potential as the ground board 30 and functions as an electromagnetic wave shield. The shield portion 70 according to the present embodiment has a ground conductor 71 and a via conductor 72. The ground conductor 71 is arranged on the rear surface 20b of the main board 20. The ground conductor 71 surrounds the patch 40 in a plan view. The ground conductor 71 is formed by patterning a metal foil arranged at the rear surface 20b of the main board 20. The ground conductor 71 includes a notch 71a. The power feeder 50 is led out to the outside of the ground conductor 71 through the notch 71a. The ground conductor 71 has a substantially C-shaped in a plan view. The ground conductor 71 faces each of the four sides of the patch 40.

The via conductor 72 is a conductor arranged in a through hole formed at the main board 20. The through hole may also be referred to as a via. The through hole penetrates the main board 20 in the Z direction. The via conductor 72 extends in the Z direction. One of the end portions of the via conductor 72 is connected to the ground board 30, and the other one of the end portions of the via conductor 72 is connected to the ground conductor 71. The shield portion 70 includes multiple via conductors 72. The via conductors 72 are arranged side by side along the extending direction of the ground conductor 71. The via conductors 72 are arranged at inter-

vals of a half wavelength or less of the operating frequency so that electromagnetic waves do not leak from the adjacent via conductors 72.

The ground conductor 71 is connected to the ground board 30 through the via conductor 72. Therefore, the outer conductor of the coaxial cable may be connected to the ground conductor 71 so that the ground board 30 provides the ground potential. The configuration of the shield portion 70 may not be limited to the above example. For example, a configuration in which the ground conductor 71 is excluded, that is, a configuration in which only the via conductor 72 is provided may be used. The arrangement of the shield portion 70 in a plan view may not be limited to the above example. The shield portion 70 may be arranged so as to face only a part of the side of the patch 40. For example, it may be arranged so as to face only one of the four sides of the patch 40.

The connection between the antenna device 10 and the power supply circuit (wireless device) is not limited to the coaxial cable. The antenna device 10 and the power supply circuit may be connected by using another communication cable such as a power supply line or a feeding line. Further, the antenna device 10 and the power supply circuit may be connected via a matching circuit, a filter circuit, or the like in addition to the coaxial cable. The antenna device 10 may be provided integrally with the power supply circuit.

Antenna Operation

The following describes the operation of the antenna device 10. The antenna device 10 configured in this way has a structure in which the ground board 30 and the patch 40 facing each other are connected by the short-circuit portion 60. This structure is a so-called mushroom structure, which is the same as a basic structure of metamaterials. Since the antenna device 10 is an antenna to which a metamaterial technology is applied, the antenna device 10 is sometimes called a metamaterial antenna.

Since the antenna device 10 is designed to operate in the zeroth-order resonant mode at a desired operating frequency, the antenna device may also be referred to as a zeroth-order resonant antenna. Among the dispersion characteristics of metamaterials, a phenomenon of resonance at a frequency at which a phase constant β becomes zero (0) is the zeroth-order resonance. The phase constant β is an imaginary part of a propagation coefficient γ of a wave propagating on a transmission line. The antenna device 10 can satisfactorily transmit and/or receive radio waves in a predetermined band including the frequency at which the zeroth-order resonance occurs.

The antenna device 10 operates by LC parallel resonance of a capacitor formed between the ground board 30 and the patch 40 and an inductor provided in the short-circuit portion 60. In the equivalent circuit described hereinafter, the capacitor formed between the ground board 30 and the patch 40 is referred to as C1, and the inductor formed in the short-circuit portion 60 is referred to as L1. In the antenna device 10, the patch 40 is short-circuited to the ground board 30 by the short-circuit portion 60 provided in the central region of the patch 40. The area of the patch 40 is an area that forms a capacitor that resonates in parallel with the inductor of the short-circuit portion 60 at a desired frequency (operating frequency). The value of the inductor is determined according to the dimension of each part of the short-circuit portion 60, for example, the diameter and the length of the short-circuit portion 60 in the Z direction. The value of the inductor may also be referred to as inductance.

Therefore, when electric power of the operating frequency is supplied, parallel resonance occurs due to energy exchange between the inductor and the capacitor, and an electric field perpendicular to the ground board 30 and the patch 40 is generated between the ground board 30 and the patch 40. That is, an electric field in the Z direction is generated. This vertical electric field propagates from the short-circuit portion 60 toward the edge portion of the patch 40 becomes vertically polarized at the edge portion of the patch 40, and propagates in space. The vertically polarized wave here refers to a radio wave in which the vibration direction of the electric field is perpendicular to the ground board 30 and the patch 40. Further, the antenna device 10 receives a vertically polarized wave coming from the outside of the antenna device 10 by LC parallel resonance.

The resonance frequency of the zeroth-order resonance does not depend on the antenna size. Therefore, the length of one side of the patch 40 can be made shorter than $\frac{1}{2}$ wavelength of the zeroth-order resonance frequency. For example, even if one side has a length equivalent to a one-quarter wavelength, zeroth-order resonance can be generated. For example, when the operating frequency is 2.44 GHz, the wavelength λ_e can be obtained by $(300 [\text{mm/s}]/2.44 [\text{GHz}])/\text{square root of the dielectric constant of the main board 20}$ in the configuration including the main board 20. It is possible to make one side shorter than a one-quarter wavelength. However, for instance, the gain such as antenna gain is reduced.

Slits and Additional Conductors

The following describes additional structures according to the present embodiment added to the basic structure of the zeroth-order resonant antenna with reference to FIGS. 1 to 7. FIG. 5 illustrates an equivalent circuit diagram of a reference example of the antenna device. In the reference example, the elements identical or related to the present embodiment are denoted by adding "r" to the tails of the reference numerals in the present embodiment. However, common reference numerals are given to the capacitors and inductors. In FIG. 5, for convenience, some circuit elements, for example, an inductor included in the patch, are omitted. FIG. 6 is a diagram in which region VI of FIG. 1 is enlarged; FIG. 6 also shows a variety of capacitors and inductors.

As FIGS. 1 and 3, in the antenna device 10 according to the present embodiment, the patch 40 has at least one slit 41. The slit 41 has a predetermined depth in the Z direction and has an aperture opening to a side surface 400 of the patch 40. The aperture may also be referred to as an opening. In particular, the side surface 400 has an aperture opening to an outer surface 400a. The side surface 400 is a surface that connects the lower surface of the patch 40 at the main board 20 and the upper surface of the main board 20 opposite to the lower surface in the Z direction. The side surface 400 is substantially parallel to the Z direction. The outer surface 400a defines or specifies the outer contour of the patch 40. The outer surface 400a is a surface derived from the outer peripheral surface of the basic shape of the patch 40. The side surface 400 has an inner surface 400b that defines or specifies a slit 41. The inner surface 400b is different from the outer surface 400a. The inner surface 400b is connected to the outer surface 400a. The inner surface 400b may also be referred to as an inner side surface. The outer surface 400a may also be referred to as an outer side surface.

The aperture of the slit 41 is formed apart from the power feeding point at the outer surface 400a of the patch 40. For example, in the planar square patch 40, the slit 41 has an

aperture at a side different from the power feeding side **40a**. The shape, size, arrangement, and number of slits **41** are not limited to the above examples. The patch **40** may have only one slit **41** or may have multiple slits **41**. The positions of the two slits **41** may be staggered in a single direction orthogonal to the Z direction. The slit **41** may be provided so as to have an aperture opening to the outer surface **400a** at the opposite side **40d**. The slit **41** is not limited to a straight line. For example, the slit **41** having a substantially L-shaped in a plan view may be adopted.

The slit **41** may be a groove provided halfway in the depth of the patch **40**. The slit **41** according to the present embodiment penetrates the patch **40** in the Z direction. The patch **40** has two slits **41**. The two slits **41** are provided so that the patch **40** has two-fold symmetry around the Z axis. When the slits **41** are provided to have two-fold symmetry, the bias of the electric field distribution can be suppressed.

The two slits **41** are provided so as to sandwich the short-circuit portion **60**, in other words, the substantially center of the patch **40** in the Y direction in a plan view. One of the slits **41** has an aperture opening to the outer surface **400a** at the adjacent side **40b**, and extends in the Y direction toward the center of the patch **40**. The other one of the slits **41** has an aperture opening to the outer surface **400a** at the adjacent side **40c**, and extends in the Y direction toward the center of the patch **40**. Each of the slits **41** has the substantially rectangular plane shape of which longitudinal direction is the Y direction. In the following, the slit **41** having an aperture opening to the adjacent side **40b** may be referred to as a slit **41b**, and the slit **41** having an aperture opening to the adjacent side **41c** may be referred to as a slit **41c**.

The extending length and width of the two slits **41b**, **41c** are equal to each other. The slits **41b**, **41c** divide the patch **40** into the first patch portion **401**, the second patch portion **402** and the third patch portion **403**. The first patch portion **401** and the second patch portion **402** have the same shape and area. The first patch portion **401** is a portion at the opposite side **40d** with respect to the slits **41b**, **41c**. The second patch portion **402** is a portion at the power feeding side **40a** with respect to the slits **41b**, **41c**. The third patch portion **403** is a portion sandwiched between the two slits **41b** and **41c**, and connects the first patch portion **401** and the second patch portion **402**. The extending length of each of the slits **41b** and **41c** is longer than the length of the third patch portion **403** in the Y direction. The respective widths of the slits **41b**, **41c** are shorter than the respective lengths of the first patch portion **401** and the second patch portion **402** in the X direction. The patch **40** includes the slits **41b**, **41c**, the first patch portion **401**, the second patch portion **402**, and the third patch portion **403** so as to form a substantially planar H-shape.

An antenna device **10r** in the reference example of FIG. 5 has a structure in which an additional conductor **80** described hereinafter is excluded from the antenna device **10** in the present embodiment. A patch **40r** has two slits (not shown) similar to the slits **41b**, **41c** as described above. A capacitor **C2** is formed between the first patch portion and the second patch portion by one of the slits. A capacitor **C3** is formed between the first patch portion and the second patch portion by the one of the slits. These capacitors **C2** and **C3** are connected in parallel to each other. The parallel circuit of the capacitors **C2**, **C3** is connected between the capacitor **C1** and the inductor **L1**. If a slit is provided in the patch **40r** and the capacitor is connected between the capacitor **C1** and the inductor **L1**, the reflection characteristics can be improved.

As illustrated in FIGS. 1, 3, 4 and 6, the antenna device **10** further includes the additional conductor **80**. The additional conductor **80** is a conductor added to the basic configuration of the zeroth-order resonant antenna. The additional conductor **80** is a conductor made of copper or the like and having the potential (ground potential) identical to the ground board **30**. The additional conductor **80** is arranged at the main board **20** so that the side surface of the additional conductor **80** faces the side surface of the patch **40** with a predetermined distance. In a plan view, the entire additional conductor **80** overlaps the ground board **30**.

The additional conductor **80** is arranged on the rear surface **20b** of the main board **20**. That is, the additional conductor **80** is arranged on the identical surface shared by the patch **40** and the power feeder **50**. The additional conductor **80** is formed by patterning a metal foil arranged at the rear surface **20b** of the main board **20**. The thickness of the additional conductor **80** is substantially equal to that of the patch **40** and the power feeder **50**. The additional conductor **80** has a base portion **81**, an inserting portion **82**, and a connecting portion **83**.

The base portion **81** extends along the outer surface **400a** of the patch **40**. The base portion **81** is arranged so as to face the outer surface **400a** around the aperture of the slit **41**. The base portion **81** may be arranged to straddle the aperture of the slit **41**, or may be arranged only on one side with respect to the slit **41**.

In the present embodiment, the base portion **81** is arranged to face the outer surface **400a** of the adjacent side **40b**. The base portion **81** faces the outer surface **400a** around the aperture of the slit **41b**. The base portion **81** faces each of the first patch portion **401** and the second patch portion **402**. The base portion **81** extends in the X-direction. With the above-mentioned arrangement, the capacitor **C5** is formed between the portion of the first patch portion **401** and the side surface of the base portion **81** at the outer surface **400a** of the adjacent side **40b**. The capacitor **C6** is formed between the portion of the second patch portion **402** and the side surface of the base portion **81** at the outer surface **400a** of the adjacent side **40b**.

The capacitance values, in other words, the electrostatic capacitance of the capacitors **C5**, **C6** are determined by the distance between the base portion **81** and the outer surface **400a** of the patch **40** and/or an opposing area formed between the base portion **81** and the outer surface **400a** of the patch **40**. The distance between the base portion **81** and the outer side surface of the patch **40** may be substantially equal in the first patch portion **401** and the second patch portion **402**, or may be different from each other. The length of the base portion **81** and the length of the patch **40** in the X direction are opposed to each other. The length, in other words, the opposing area may be substantially equal in the first patch portion **401** and the second patch portion **402**, or may be different from each other. The respective values of the capacitors **C5**, **C6** can be adjusted according to the distance and/or the opposing area (in other words, the opposing length).

In the present embodiment, the base portion **81** is arranged to face the entire region of the adjacent side **40b**. The base portion **81** is arranged to face the part of the adjacent side **40b** from the boundary formed with the opposite side **40d** to the boundary formed with the power feeding side **40a**. The distance between the base portion **81** and the outer surface **400a** of the patch **40** is substantially constant over the total length of the base portion **81**.

The inserting portion **82** is connected to the base portion **81**, and is arranged in the slit **41** to face the inner surface

400b of the patch 40. The connecting position of the inserting portion 82 with respect to the base portion 81 is not particularly limited. In the present embodiment, the inserting portion 82 extends in the Y direction. The inserting portion 82 has the substantially rectangular plane shape of which longitudinal direction is the Y direction. The side surface of the inserting portion 82 faces each of the inner surface 400b of the first patch portion 401, the inner surface 400b of the second patch portion 402 and the inner surface 400b of the third patch portion 403. The inserting portion 82 is connected to the central portion of the base portion 81 in the X direction.

With the above-mentioned arrangement, the capacitor C21 is formed between the inner surface 400b of the first patch portion 401 and the side surface of the inserting portion 82. The capacitor C22 is formed between the inner surface 400b of the third patch portion 403 as the base of the slit 41 and the side surface of the inserting portion 82. The capacitor C23 is formed between the inner surface 400b of the second patch portion 402 and the side surface of the inserting portion 82. The parallel circuit of the capacitors C21, C22 and C23 is equivalent to the above-mentioned capacitor C2.

The respective capacitance values of the capacitors C21, C22 and C23 are determined by the distance between the inserting portion 82 and the inner surface 400b of the patch 40 and/or an opposing area formed between the inserting portion 82 and the inner surface 400b of the patch 40.

For example, the distance between the inserting portion 82 and the inner surface 400b may be substantially equal in the first patch portion 401 and the second patch portion 402, or may be different from each other. The respective lengths of the inserting portion 82 and the length of the inner surface 400b in the extending direction of the inserting portion 82 are opposed to each other. The opposing length, in other words, the opposing area may be substantially equal in the first patch portion 401 and the second patch portion 402, or may be different from each other. The respective values of the capacitors C21, C22 and C23 can be adjusted according to the distance between the inserting portion 82 and each of the patch portions 401, 402 and 403 and/or the opposing area (in other words, the opposing length). In the present embodiment, the distance between the inserting portion 82 and the inner surface 400b is substantially constant over the total length of the opposing area.

The connecting portion 83 is a portion of the additional conductor 80 that electrically connects the other portion, that is, the base portion 81 and the inserting portion 82 to the ground board 30. The connection portion 83 extends from the base portion 81 and includes the inductor L2. As the connecting portion 83, for example, a conductor arranged at the rear surface 20b of the main board 20 and connected to the base portion 81, a via conductor connected to the base portion 81 and a combination of the conductor arranged at the rear surface 20b and the via conductor may be adopted.

In the present embodiment, the connecting portion 83 is a conductor connected to the base portion 81. The connecting portion 83 is integrally formed with the base portion 81 and the inserting portion 82 by patterning the metal foil. The connecting portion 83 extends from the base portion 81 to a side opposite to the inserting portion 82 in the Y direction. One of the end portions of the connecting portion 83 is connected to the base portion 81. The other one of the end portions of the connecting portion 83 is connected to the ground conductor 71 included in the shield portion 70. The additional conductor 80 has the potential (ground potential) identical to the ground board 30 by connecting the connect-

ing portion 83 electrically to the ground conductor 71. The inductance value of the inductor L2 included in the connecting portion 83 is determined according to the length and width of the conductor in the extending direction.

FIG. 7 is an equivalent circuit diagram of the antenna device 10 according to the present embodiment. In FIG. 7, for convenience, some circuit elements, for example, an inductor included in the patch, are omitted.

As described above, in the present embodiment, the 10 inserting portion 82 of the additional conductor 80 forms the capacitors C21, C22 and C23 with the inner surface 400b that defines the slit 41 or 41b at the patch 40. By arranging the inserting portion 82 in the slit 41b, the capacitor C2 in the reference example of FIG. 5 is replaced with the parallel 15 circuit of the capacitors C21, C22 and C23. As illustrated in FIG. 7, the parallel circuit having the capacitors C3, C21, C22 and C23 is connected between the capacitor C1 and the inductor L1.

The base portion 81 of the additional conductor 80 forms 20 the capacitors C5, C6 with the outer surface 400a of the patch 40. The parallel circuit having the capacitors C5 and C6 is connected to the ground board 30 through the inductor L2 of the connecting portion 83. As illustrated in FIG. 7, an LC circuit having the inductor L2 and the capacitors C5 and 25 C6 is formed between the ground board 30 and the patch 40. The LC circuit is connected to the capacitor C1 and the inductor L1 in parallel.

Summary of First Embodiment

FIGS. 8 to 11 illustrate the results of electromagnetic field simulation of the antenna device at the printed circuit board. FIG. 8 illustrates the reflection characteristics. In FIG. 8, a one-dot chain line and a two-dot chain line respectively indicate the results of the antenna device in the reference examples. The antenna device in the reference example includes the basic structure of the zeroth-order resonant antenna without the slit and the additional conductor. In other words, the antenna device in the reference example has a zeroth-order resonant antenna having a comparative structure. The one-dot chain line indicates the result of the first reference example, and the two-dot chain line indicates the result of the second reference example. The solid line indicates the antenna device 10 in the present embodiment, in other words, the result in the present example. In the reference example and the present embodiment, the operating frequency, the configuration such as dielectric constant and thickness of the main board, and the diameter of the short-circuit portion are the same.

The zeroth-order resonant antenna (metamaterial antenna) configured at the printed circuit board may have a change in the frequency band with respect to the resonant frequency of the target due to a variety of reasons such as a change in the dielectric along with the modification of the material of the main board. For the above reason, in the first reference example, the frequency band is deviated from the resonance frequency (2.44 GHz) of the target. As shown in FIG. 8, the frequency band of the first reference example is shifted to the lower frequency side with respect to the target. FIG. 9 indicates the reflection characteristics (electrical field distribution) in the first reference example. The maximum gain of the first reference example was -11.8 dB at 2.44 GHz. The antenna gain is reduced due to the deviation of the frequency band.

The zeroth-order resonant antenna having the basic structure at the printed circuit board operates by LC parallel resonance between the inductor L1 of the via conductor

included in the short-circuit portion and the capacitor C1 formed between the patch and the ground board. The inductor L1 is determined by the thickness of the main board and the via diameter, and the capacitor C1 is determined by the size of the patch and the thickness of the main board. The thickness of the main board is limited by other circuit configurations formed at the printed circuit board. As described above, there are few parameters that determine the resonance frequency.

The size of the patch, the via diameter of the short-circuit portion, and the size of the ground board are adjusted to enhance the reflection characteristics. To change the size of the antenna, it is necessary to consider the circuit layout around the antenna at the printed circuit board. Further, the via diameter cannot be made smaller than a predetermined diameter because it is restricted by processing such as a drill. When the frequency is shifted to the low frequency side with respect to the target as in first reference example, the resonance frequency cannot be increased unless the size of the patch portion is reduced.

In the second reference example, the size of the patch is smaller than that of the first reference example in order to increase the resonance frequency. As described above, when the size of the patch is reduced, not only the opposing area formed between the patch and the ground board but also the value of the capacitor C1 becomes smaller. As a result, the resonance frequency of the second reference example is shifted to the higher frequency side with respect to the first reference example as shown in FIG. 8. On the other hand, since the radiation area decreases, the gain of the antenna decreases. FIG. 10 illustrates the reflection characteristics in the second reference example. The maximum gain of the second reference example was -9.7 dB at 2.44 GHz due to the decrease in radiation area even though the resonance frequency was shifted to the vicinity of the target.

Since the zeroth-order resonant antenna has a maximum gain lower than the first-order resonant antenna, it may be desirable to change the design without decreasing the original gain. Since the via diameter is often limited in processing, the size of the patch is the main parameter for adjusting the resonance frequency and enhancing the reflection characteristics in the zeroth-order resonance antenna having the basic structure. Therefore, it affects the antenna gain.

On the other hand, according to the antenna device 10 in the present embodiment, the additional conductor 80 is added to the basic structure of the zeroth-order resonant antenna. A capacitor is formed at a portion where the base portion 81 of the additional conductor 80 faces the outer surface 400a of the patch 40. The connecting portion 83 of the additional conductor 80 includes an inductor. Since new parameters are added in the LC parallel resonant circuit, the degree of freedom in designing the antenna device 10 is enhanced. While configuring the size of the patch 40 identical to the one in the first reference example, the resonance frequency can be shifted to the higher frequency side as shown in FIG. 8 to match the target. In other words, the resonance frequency can be shifted to the higher frequency side without reducing the size of the patch 40.

The patch 40 is provided with a slit 41. Since the area of the patch 40 is reduced by the slit 41, the capacitance value of the capacitor C1 is reduced. On the other hand, the slit 41 connects the capacitor between the capacitor C1 and the inductor L1 as shown in the above-mentioned reference example in FIG. 5. Therefore, the parameters for determining the entire capacitors increase. By providing the slit 41, the degree of freedom in designing the antenna device 10 is

enhanced. It is possible to enhance the reflection characteristics as compared with a situation of having no slit 41.

In the present embodiment, the inserting portion 82 of the additional conductor 80 is arranged inside the slit 41. 5 Multiple capacitors are formed at a portion where the inserting portion 82 of the additional conductor 80 faces the inner surface 400b of the patch 40. As a result, the parameters can be further increased, and the degree of freedom in designing the antenna device 10 can be further enhanced. 10 Therefore, as shown in FIG. 8, the reflection characteristics can be further enhanced. According to the present embodiment, the reflection characteristics can be further enhanced as compared with the configuration in which the inserting portion is not arranged in the slit as shown in FIG. 5.

According to the antenna device 10 in the present embodiment, it is possible to enhance the reflection characteristics while shifting the resonance frequency to the higher resonance frequency side without changing the physical size of the patch 40. Since the physical size (outer contour) of the patch 40 is not changed, it is possible to enhance the antenna gain. FIG. 11 illustrates the radiation characteristics in the present example. The maximum gain of the present example was -7.8 dB at 2.44 GHz.

20 In the present embodiment, the patch 40 having a substantially square planar shape includes a slit 41b and a slit 41c. The slit 41b has an aperture opening to the adjacent side 40b, and the slit 41c has an aperture opening to the adjacent side 40c. The effect of enhancing the reflection characteristics is higher in a situation where the slit 41 is provided on at least one of the adjacent sides 40b and 40c as compared with a situation where the slit 41 is provided at the opposite side 40d. The slits 41b and 41c correspond to adjacent slits.

25 In the present embodiment, the inserting portion 82 of the additional conductor 80 is arranged at only the slit 41b from both of the slits 41b and 41c. According to this situation, the electric field distribution is biased to the side where the inserting portion 82 is provided, and the directivity can be biased to the slit 41b side in the Y direction. In the present embodiment, the power feeder 50 has a substantially L-shaped planar shape, and has a portion extending in the Y direction toward the slit 41b. As a result, the directivity is biased toward the slit 41b in the Y direction. A synergistic effect of the arrangement of the power feeder 50 and the arrangement of the inserting portion 82 can be anticipated. The slit 41b corresponds to a first adjacent slit, and the slit 41c corresponds to a second adjacent slit.

In the present embodiment, the base portion 81 is arranged to face the outer surface 400a across the aperture of the slit 41b. In other words, the base portion 81 is arranged to face the outer surface 400a of the first patch portion 401 and the outer surface 400a of the second patch portion 402. As a result, the above-mentioned capacitors C5 and C6 are formed. With an increase in the parameters, it is possible to enhance the degree of freedom in designing the antenna device 10. Since finer adjustment is possible by enhancing the degree of freedom in design, it is easier to match the resonance frequency with the resonance frequency of the target.

60 In the present embodiment, the connecting portion 83 includes a conductor connected to the base portion 81. In other words, at least a portion of the connecting portion 83 closer to the base portion 81 is disposed at a surface at which the base portion 81 is disposed. As a result, the distance between the base portion 81 and the outer surface 400a of the patch 40 can be narrowed as compared with the configuration in which the via conductor of the connecting

portion **83** is connected to the base portion **81**. Accordingly, it may be possible to improve freedom of design of the antenna device **10**.

FIG. 12 indicates a change in the reflection characteristics depending on the position of the connecting portion **83** in the antenna device **10**. FIG. 13 illustrates the arrangement of the connecting portion **83** with respect to the base portion **81**. In the electromagnetic field simulation, the center of the portion of the second patch portion **402** facing the base portion **81** in the X direction was set as the reference position of the connecting portion **83**. The center illustrated in FIG. 12 indicates the reflection characteristics in a situation where the connecting portion **83** is adopted as a reference position. The movement to XR shown in FIG. 12 indicates the reflection characteristics in a situation where the connecting portion **83** is moved from the reference position by a predetermined distance in XR direction as shown in FIG. 13. The movement to XL shown in FIG. 12 indicates the reflection characteristics in a situation where the connecting portion **83** is moved from the reference position by a predetermined distance in XL direction as shown in FIG. 13. The XR direction is a direction from the reference position toward the power feeding side **40a** in the X direction. The XL direction is a direction from the reference position toward the opposite side **40d** in the X direction. In the electromagnetic field simulation, the base portion **81** has a length substantially equal to the adjacent side **40b** of the patch **40**.

In a situation where the connecting portion **83** is set closer to XR from the reference position, the high-frequency shifting amount of the resonance frequency is smaller than the reference position as indicated by a one-dot chain line in FIG. 12. In a situation where the connecting portion **83** is set closer to XL from the reference position, the high-frequency shifting amount of the resonance frequency is larger than the reference position as indicated by a broken line in FIG. 12. In a situation where the connecting portion **83** moves to the XR side, the distance from the short-circuit portion **60** to the connecting part where the ground conductor **71** is connected to the connecting portion **83** becomes longer. In other words, the connecting part is a ground connecting portion at the additional conductor **80**. As a result, the high-frequency shifting amount decreases. In a situation where the connecting portion **83** moves to the XL side, the distance from the short-circuit portion **60** to a connecting part where the ground conductor **71** is connected to the connecting portion **83** becomes longer, and the high-frequency shifting amount decreases.

In other words, in a situation where the connecting portion **83** is connected closer to the short-circuit portion **60** than the end portion of the base portion **81** in the extending direction, in other words, the X direction, it is possible to further increase the high-frequency shifting amount. In a situation where the connecting portion **83** is connected to the end part of the base portion **81** in the extending direction, it is possible to decrease the high-frequency shifting amount.

Modified Example

The above describes an example in which the inserting portion **82** of the additional conductor **80** is arranged at the slit **41b** of the adjacent side **40b**, the present disclosure is not limited to this situation. For example, as shown in the modified example in FIG. 14, the additional conductor **80** may also be provided at the slit **41c** in the configuration where the patch **40** has two slits **41b**, **41c**. In FIG. 14, the base portion **81** of the additional conductor **80** faces the

outer surface **400a** of the adjacent side **40c**. The inserting portion **82** is arranged in the slit **41c** and faces the inner surface **400b**. The connecting portion **83** extends from the base portion **81** to the side away from the patch **40** in the Y direction.

As shown in the modified example of FIG. 15, the additional conductor **80** may be arranged at each of the two slits **41b**, **41c**. The antenna device **10** includes two additional conductors **80b** and **80c**. The inserting portion **82** of the additional conductor **80b** is arranged at the slit **41b**. The inserting portion **82** of the additional conductor **80c** is arranged at the slit **41c**.

As shown in the modified example of FIG. 16, the patch **40** may have a slit **41d** having an aperture opening to the opposite side **40d**. The antenna device **10** may include the additional conductor **80d** at the slit **41d**. The inserting portion **82** of the additional conductor **80d** is arranged at the slit **41d**. In FIG. 16, the patch **40** has three slits **41b**, **41c**, and **41d**. In the present embodiment, the additional conductor **80** is arranged at the two slits **41b**, **41c** among the three slits **41b**, **41c**, and **41d**. Although only the slit **41d** may be provided, the slits **41b** and **41c** that respectively have apertures opening to the adjacent sides **40b** and **40c** are more effective in enhancing the reflection characteristics.

FIG. 17 is a diagram in which region XVII of FIG. 15 is enlarged. As shown in FIG. 17, capacitors **C7**, **C8**, **C31**, **C32**, and **C33** are formed between an additional conductor **80c** and the patch **40**. The capacitor **C7** is formed between the base portion **81** and the outer surface **400a** of the first patch portion **401**. The capacitor **C8** is formed between the base portion **81** and the outer surface **400a** of the second patch portion **402**. The capacitor **C31** is formed between the inserting portion **82** and the inner surface **400b** of the first patch portion **401**. The capacitor **C32** is formed between the inserting portion **82** and the inner surface **400b** of the third patch portion **403**. The capacitor **C33** is formed between the inserting portion **82** and the inner surface **400b** of the second patch portion **402**. The connecting portion **83** includes the inductor **L3**.

FIG. 18 is an equivalent circuit diagram of the modified example illustrated in FIG. 15. With the addition of the additional conductor **80c**, the capacitor **C3** is replaced with a parallel circuit having the capacitors **C31**, **C32** and **C33**. The parallel circuit having the capacitors **C21**, **C22**, **C23**, **C32** and **C33** is connected between the capacitor **C1** and the inductor **L1**. An LC circuit having the inductor **L3** and the capacitors **C7** and **C8** is formed between the ground board **30** and the patch **40**. The LC circuit having the inductor **L3** and the capacitors **C7**, **C8** is connected in parallel to the LC circuit having the inductor **L2** and the capacitors **C5**, **C6**. Since the parameters are further increased by increasing the number of additional conductor **80**, it is possible to enhance the degree of freedom in designing the antenna device **10**.

As shown in the modified example of FIG. 19, one additional conductor **80** may have multiple connecting portions **83**. In FIG. 19, two connecting portions **83** are connected to one base portion **81**. The base portion **81** and the connecting portion **83** have a substantially F-shaped planar shape.

As shown in the modified example of FIG. 20, the extended length of the base **81** may be shorter than the length of the side where the slit **41** opens. In FIG. 20, the extended length of the base **81** is shorter than the length of the adjacent side **40b**. The base portion **81** faces the entire region of the first patch portion **401** at the adjacent side **40b**, and faces only a part of the second patch portion **402** at the adjacent side **40b**. Since the opposed area formed between

the base portion **81** and the second portion **402** is smaller, the capacitance value of the capacitor **C6** becomes smaller.

In FIG. 20, the connecting portion **83** is connected to the end portion of the base portion **81** in the extending direction of the base portion **81**. On the other hand, as shown in the modified example of FIG. 21, the connecting portion **83** may be connected to a position closer to the short-circuit portion **60** than the end portion of the base portion **81** in the extending direction. As described above, it is possible to further increase the high-frequency shifting amount.

As in the modified example of FIG. 22, the connecting portion **83** of the additional conductor **80** may include a conductor **83a** arranged at the rear surface **20b** and a via conductor **83b**. Although not shown, the connecting portion **83** may only include the via conductor **83b** and exclude the conductor **83a**.

Second Embodiment

A second embodiment is a modification of the preceding embodiments as a basic configuration and may incorporate the description of the preceding embodiments. In the prior embodiment, the power feeder **50** is connected to the patch **40**. Instead, the power feeder **50** may form a capacitor with the patch **40**.

FIG. 23 illustrates the antenna device **10** according to the present embodiment. FIG. 24 is a diagram in which region XXIV of FIG. 23 is enlarged. As illustrated in FIGS. 23 and 24, the power feeder **50** is not connected to the patch **40** in the antenna device **10** according to the present embodiment. The power feeder **50** forms a capacitor with the patch **40**, and is electrically connected to the patch **40** through this capacitor. The power feeder **50** has a branch portion **51**. The branch portion **51** is provided at the end portion of the power feeder **50** near the patch **40**. The branch portion **51** is branched into several branches. In the present embodiment, the branch portion **51** is branched into three branches. The branch portion **51** includes a base **51a** and three protrusions **51b** extending from the base **51a** in the X direction.

The second patch portion **402** of the patch **40** includes a notch **42** for individually accommodating each of the protrusions **51b** of the branch portion **51**. The notch **42** has an aperture opening to the outer surface **400a** of the patch **40**. The side surface **400** has an inner surface **400c** that defines or specifies the notch **42**. The inner surface **400c** is connected to the outer surface **400a** of the power feeding side **40a**. The notch **42** includes three recesses for respectively accommodating the protrusions **51b**, and includes two protrusions between the adjacent recesses.

The branch portion **51** is arranged to face the inner surface **400c** with a predetermined distance. With the above-mentioned arrangement, capacitors **C9**, **C10** and **C11** are formed between the respective tip surfaces of the protrusions **51b** and the inner surface **400c** forming the bottom of the recess. Capacitors **C12**, **C13**, **C14**, **C15**, **C16**, and **C17** are formed between the both side surfaces of the protrusions **51b** and the inner surface **400c**. Capacitors **C18** and **C19** are formed between the base **51a** and the inner surface **400c** forming the tip of the protrusion. The branch portion **51** passes through the short-circuit portion **60** in a plan view, and is linearly symmetric with respect to a virtual straight line parallel to an X-axis. Similarly, the notch **42** is linearly symmetric with respect to the above-mentioned virtual straight line. The power feeder **50** includes an inductor **L4**. Since the other configurations are similar to the configurations described in the preceding embodiment, the description of the other configurations is not described in the following.

FIG. 25 is an equivalent circuit diagram of the antenna device **10** according to the present embodiment. As described above, in the present embodiment, the power feeder **50** includes the inductor **L4**. The branch portion **51**, which is provided at the end portion of the power feeder **50**, forms capacitors **C9** to **C19** with the inner surface **400c** of the patch **40**. These capacitors **C9** to **C19** are connected in parallel to each other. The LC circuit having the inductor **L4** and the capacitors **C9** to **C19** is connected in parallel to the LC circuit having the inductor **L2** and the capacitors **C15**, **C6**.

Summary of Second Embodiment

FIG. 26 illustrates the results, in other words, the reflection characteristics of electromagnetic field simulation of the antenna device **10** according to the present embodiment. In FIG. 26, the result of the preceding embodiment is shown by a broken line as a reference example. The results of the preceding embodiment correspond to the solid line in FIG. 8. The solid line indicates the results of the antenna device **10** in the present embodiment. In the electromagnetic field simulation of the present embodiment, the configuration such as the dielectric constant and the thickness of the main board and the diameter of the short-circuit portion are identical to those of the simulation of the preceding embodiment.

The antenna device **10** according to the present embodiment includes the patch **40** having the slit **41** and the additional conductor **80**. Therefore, it is possible to generate an advantageous effect identical to the configuration described in the first embodiment. In other words, it is possible to enhance the reflection characteristics while shifting the resonance frequency to the higher resonance frequency side without changing the physical size of the patch **40**.

The power feeder **50** forms a capacitor or capacitance with the patch **40**. The capacitance value of the capacitor is sufficiently small as compared with the capacitors **C5**, **C6** near the additional conductor **80** to be connected in parallel with the capacitor. As compare with the total number of capacitors included in respective LC circuits, the capacitance value of the capacitor near the power feeder **50** is, for example, about 1/50 to 1/1000 of the capacitance value of the capacitor near the additional conductor **80**. The inductance value of the inductor **L4** included in the power feeder **50** is sufficiently small as compared with the inductor **L2** included in the connecting portion **83** of the additional conductor **80**. Therefore, the LC circuit near the power feeder **50** enhances the impedance matching with the antenna, in other words, the reflection characteristics, but without having a remarkable enhancement on the high-frequency shift.

Since new parameters are added in the LC parallel resonant circuit, the degree of freedom in designing the antenna device **10** is enhanced. In other words, as illustrated in FIG. 26, it is possible to enhance the reflection characteristics while shifting the resonance frequency to the higher resonance frequency side without changing the physical size of the patch **40**. FIG. 27 illustrates the radiation characteristics in the present example. The maximum gain of the present example was -7.3 dB at 2.44 GHz.

In the present embodiment, the power feeder **50** includes the branch portion **51** at the end portion near the patch **40**. The branch portion **51** forms capacitors **C9** to **C19** with the inner surface **400c** included in the notch **42** of the patch **40**. With an increase in the parameters, it is possible to enhance

19

the degree of freedom in designing the antenna device 10. Since it is possible to have a fine adjustment with the enhancement in the degree of freedom in design, it is possible to further enhance the reflection characteristics.

Modified Example

The shape, size, arrangement, and number of slits 41 and additional conductors 80 are not limited to the above examples. Combinations with the configuration described in the preceding embodiment are also possible. For example, as shown in the modified example of FIG. 28, the connecting structure in which the power feeder 50 and the patch 40 are connected may be combined with the configuration including the patch 40 with two slits 41b, 41c and two additional conductors 80b, 80c. In FIG. 28, the slits 41b, 41c are arranged to be deviated to each other. The slits 41b, 41c do not sandwich the short-circuit portion 60 in the Y direction. The patch 40 having the slits 41b and 41c has two-fold symmetry around the Z axis.

The present disclosure describes the example in which the branch portion 51 has three protrusions 51b. However, the present disclosure is not limited to this example. For example, as shown in the modified example of FIG. 29, the branch portion 51 may have five protrusions 51b. As the number of protrusions increases, the parameters are further increased.

The present disclosure describes the example in which the power feeder 50 includes the branch portion 51. However, the present disclosure is not limited to this example. At least one capacitor may be formed between the power feeder 50 and the patch 40. For example, the end portion of the part of the power feeder 50 extending in the X direction may be arranged to face the outer surface 400a of the power feeding side 40a of the patch 40 to form the capacitor. A portion of the power feeder 50 may be arranged at the notch 42 to form multiple capacitors.

Other Embodiments

The disclosure in this specification and drawings etc. is not limited to the above-described embodiments. The disclosure encompasses the above-described embodiments and modifications based on the embodiments by those skilled in the art. For example, the disclosure is not limited to the combinations of parts and/or elements shown in the embodiments. The present disclosure may be implemented in various combinations. The disclosure may have additional parts that may be added to the embodiments. The disclosure covers omissions of parts and/or elements of the embodiments. The disclosure covers replacement or combination of components, elements between one of the embodiments and another. The disclosed technical scope is not limited to the description of the embodiments.

What is claimed is:

1. An antenna device comprising:
a main board made of a dielectric material;
a ground board disposed at the main board and configured to supply a ground potential;
a patch disposed at the main board to face the ground board in a thickness direction of the main board;
a power feeder disposed at the main board and electrically connected to the patch;
a short-circuit portion including a via conductor disposed at the main board, and electrically connected to the patch and the ground board; and

20

an additional conductor disposed at the main board such that a side surface of the additional conductor faces a side surface of the patch, and having a potential identical to the ground potential of the ground board, wherein the patch includes:

an outer surface configured to define an outer contour of the patch, the outer surface being the side surface of the patch;
at least one slit having an aperture opening to a position that is apart from a part of the outer surface electrically connected with the power feeder; and
an inner surface configured to define the slit, the inner surface being the side surface of the patch, and wherein the additional conductor includes:

a base portion that extends in an extending direction along the outer surface of the patch, and that is disposed to face the outer surface around the aperture of the slit;

an inserting portion that is connected to the base portion, and that is disposed inside the slit to face the inner surface of the patch; and

a connecting portion that extends from the base portion, and that electrically connects the ground board and the additional conductor.

2. The antenna device according to claim 1, wherein the patch has a rectangular shape in a planar view along the thickness direction, wherein the patch further includes:

a power feeding side electrically connected with the power feeder;

an adjacent side as a side of the patch adjacent to the power feeding side;

an opposite side disposed at a side opposite to the power feeding side,

wherein the slit has at least an adjacent slit opening to the outer surface at the adjacent side, and wherein the additional conductor is disposed in at least the adjacent slit.

3. The antenna device according to claim 2, wherein the adjacent side includes a plurality of adjacent sides having a first adjacent side and a second adjacent side,

wherein the adjacent slit includes a plurality of adjacent slits,

wherein the adjacent slits includes:

a first adjacent slit opening to the outer surface at the first adjacent side; and

a second adjacent slit opening to the outer surface at the second adjacent side, and

wherein the additional conductor is disposed at one of the first adjacent slit and the second adjacent slit.

4. The antenna device according to claim 1, wherein the base portion is disposed across the aperture of the slit in which the inserting portion connected to the base portion is disposed, and the base portion is disposed to face the outer surface.

5. The antenna device according to claim 1, wherein at least a part of the connecting portion extending from the base portion is disposed at a surface of the main board at which the base portion is disposed.

6. The antenna device according to claim 5, wherein the connecting portion is connected to a position closer to the short-circuit portion than to an end portion of the base portion in the extending direction.

7. The antenna device according to claim 5, wherein the connecting portion is connected to an end portion of the base portion in the extending direction.

8. The antenna device according to claim 1,
wherein a capacitor between the power feeder and the
patch has a smaller capacitance value than a capacitor
between the base portion and the patch.
9. The antenna device according to claim 8,
wherein the power feeder has a branch portion that is
branched into a plurality of branches, at an end portion
of the power feeder near the patch, and
wherein the patch has a notch opening to the outer surface
for accommodating the branch portion. 5 10
